UNITED STATES PATENT OFFICE.

JESSE L. LEWIS, OF ALLENTOWN, PENNSYLVANIA.

ENVELOPE SEAL.

Application filed January 10, 1924. Serial No. 685,448.

To all whom it may concern:

Be it known that I, JESSE L. LEWIS, a citizen of the United States, residing at Allentown, in the county of Lehigh and State of 5 Pennsylvania, have invented certain new and useful Improvements in Envelope Seals, of which the following is a specification.

This invention relates to envelopes of the kind used for mailing purposes. More particularly the invention relates to an envelope having a self locking flap so constructed and arranged that once the envelope is closed it can only be opened either by tearing the material of the envelope itself 15 or by destroying the locking device.

One important object of the invention is to improve and simplify the general construction of devices of this character.

A second important object of the invention 20 is to provide an envelope having a flap, the body and flap being equipped with novel locking means made from metallic wire or strips and so arranged that once locked it cannot be disengaged without destruction.

25 A third important object of the invention is to provide an improved locking device for envelopes which may be applied to any of the ordinary shapes of envelopes without requiring special manufacture of the latter.

30 With the above and other objects in view as will be hereinafter apparent, the invention consists in general of certain novel details of construction and combinations of parts hereinafter fully described, illustrated in the 35 accompanying drawings and specifically claimed.

In the accompanying drawings—

Figure 1 is a face view of an envelope in its opened position showing the device applied thereto.

40 Figure 2 is an enlarged detail section on the line 2—2 of Figure 1 with the envelope in its locked position.

45 Figure 3 is an enlarged detail perspective view showing the lock parts in locked position.

In the embodiment of the invention here disclosed there is shown an end opening envelope having a back 11 and a front 12, the 50 latter being provided with a closing flap 13 arranged to be doubled over the back in the usual manner. Extending across the back of the envelope adjacent its mouth is a main locking bar having its ends 14 within the envelope and the extremity of said ends

bent as shown at 15 within the envelope to prevent the bar from turning. The center portion of this locking bar is offset as at 16 and projects through suitable openings in the back 11 so as to form a species of eye. The end portion of the flap 13 is doubled upon itself and embraces the ends 17 of a loop member provided with a centrally disposed and flattened loop 18 so arranged that, when the flap is closed down 60 this loop member may be hooked behind the central portion 16 of the main locking bar. Fixed to the back 11 and extending beneath the portion 16 is a latch member which has a body portion 19 and is provided on 65 one extremity with means for securing this extremity to the back 11, the means here shown being a cross bar 20 provided with gripping points 21 intended to be forced through the back 11 and gripped down thereon. This latch or finger has its other extremity offset as at 22 and provided with a rebent terminal portion 23.

70 Now in operation when the loop 18 is engaged beneath the portion 16 of the main lock bar this loop is slid up by the body 19 of the latch and this portion 16 until the extremity of the loop slides over the rebent end 23 of the latch whereupon it drops down beneath the latch and locks so that 75 it cannot again be freed from this latch to unlock and permit opening of the envelope.

80 There has thus been provided a simple and efficient device of the kind described and for the purpose specified.

85 It is obvious that minor changes may be made in the form and construction of the invention without departing from the material spirit thereof. It is not, therefore, desired to confine the invention to the exact 90 form herein shown and described, but it is desired to include all such as properly come within the scope claimed.

95 Having thus described the invention, what is claimed as new, is:

100 1. The combination with an envelope body and its flap; of a locking bar carried by the envelope body and forming an eye, a loop member carried by the flap to hook behind the eye, and a latch finger carried by the envelope body and engaging in the loop member upon the latter being hooked through the eye.

105 2. The combination with an envelope body and its flap; of a locking bar carried 110

by the envelope body and forming an eye, a loop member carried by the flap to hook behind the eye, and a latch finger having one end secured to the envelope body and extending from said secured end towards the mouth of the envelope beneath the eye, the free extremity of the latch finger being offset away from the envelope body and re-

bent whereby to engage and hold the loop member.

In testimony whereof I affix my signature in the presence of two witnesses.

JESSE L. LEWIS.
